RALPH S. TYLER, OF CLEVELAND HEIGHTS VILLAGE, OHIO, ASSIGNOR TO THE CHANDLER AND PRICE COMPANY, OF CLEVELAND, OHIO, A CORPORATION OF OHIO.

INKING MECHANISM FOR PRINTING-PRESSES.

1,352,159.

Specification of Letters Patent. Patented Sept. 7, 1920.

Application filed April 23, 1919. Serial No. 292,137.

To all whom it may concern:

Be it known that I, RALPH S. TYLER, a citizen of the United States, and a resident of Cleveland Heights Village, county of 5 Cuyahoga, and State of Ohio, have invented a new and useful Improvement in Inking Mechanism for Printing-Presses, of which the following is a specification, the principle of the invention being herein explained and 10 the best mode in which I have contemplated applying that principle, so as to distinguish it from other inventions.

The present improvements, relating, as indicated, to inking mechanism for printing 15 presses, have more particular regard to an automatic ink fountain for platen presses, a fountain of this type being illustrated, for example, in U. S. Letters Patent Re. No. 14,165, granted A. B. Cartt under date of 20 July 18, 1916. One of the objects of the present invention is to provide means for rendering such an automatic ink fountain inoperative whenever the throw-off lever is 25 swung to prevent contact between platen and form. Another object is to provide means whereby the amount of ink distributed onto the inking plate or disk, and thence by means of the form rollers onto the form, may be adjusted or controlled.

30 To the accomplishment of the foregoing and related ends, the invention, then, consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

40 In said annexed drawing:—

Figure 1 is a side elevation of a Gordon platen press equipped with an automatic ink fountain of the kind previously referred to, said fountain being adapted to be thrown 45 out of operation whenever the throw-off lever of the press is swung rearwardly and being formed adjustable to vary the rate at which the ink is fed in accordance with the present invention; Fig. 2 is a side elevation 50 on an enlarged scale of a detail of such fountain; and Fig. 3 is a cross-section of such detail, the plane of the section being indicated by the line 3—3, Fig. 1.

The press is of familiar construction, comprising a platen 1 suitably supported on a

frame 2 and an oscillatory form-carrying bed 3 that is swung toward and away from said platen through the medium of cranks 4 and connecting rods or side arms 5. By means of a rock shaft 6 and connections (not 60 shown) the position of the bed may be shifted, so that, without interrupting its oscillation, or in other words stopping the press, the form 8 does not contact with platen 1. This is a familiar feature of construction in 65 presses of the class in hand, it being frequently necessary to thus "throw off" the press if the sheet on the platen slips or is not properly adjusted in position. For the purpose of operating said rock shaft 6 a 70 lever 9 pivotally attached to the side of the frame 2 is provided, said lever being connected by means of a link 10 with a lever 11 on said shaft 6.

The automatic ink fountain shown in the 75 drawing, as previously indicated, is of the type disclosed in Reissue Letters Patent No. 14,165, and comprises a frame 15 suitably attached to the bed at the rear of the disk 16 and overhanging the latter, so as to leave 80 ample clearance for the form rollers 17 which are moved over said disk and the form 8 by the oscillation of the roller frame 18, as need not be further explained.

The fountain proper comprises a suitable 85 receptacle 20, in which a roller (not shown) is suitably supported on the shaft 21. From this roller the ink is carried onto an intermediate roller 22 that is adapted to contact with the form rollers 17 as the latter 90 pass across the disk. For the purpose of imparting rotative movement to the roller on shaft 21 an arm 23 is oscillatorily mounted about the same axis as said shaft, said arm carrying a pawl or dog 24 that 95 is adapted to coöperate with a ratchet 25, keyed or otherwise fixedly attached to the shaft (see Fig. 3). The outer or free end of said lever 23 is adjustably connected, by means of a rod 26, with the roller frame 18, 100 so that, as the latter oscillates to move the form rollers 17 back and forth across the disk and form, an oscillatory movement is at the same time imparted to said arm. As a result of this movement, the dog 24 is 105 adapted to impart to the ratchet wheel 25, and thus to the shaft 21, a rotative movement through a predetermined arc for every oscillation of the form roller frame.

The effect of the rotation of the shaft 21 110

and roller carried thereby will obviously be to feed the same predetermined quantity of ink, irrespective of requirements which may vary with the nature of the job and 5 the character of the ink used. I accordingly provide means for limiting the operative effect of the dog 24 as follows, viz: On the shaft 21 adjacent the ratchet wheel 25 I mount a disk 30, the diameter of which, 10 for a portion of its circumference, is equal to or greater than the maximum diameter of said ratchet wheel so as to shroud the teeth thereon. Accordingly, by rotating the disk so as to bring this portion of its periphery 15 into the path of the dog 24, the effect of the latter to rotate said wheel will be correspondingly limited. Said disk 30 may be thus positioned manually as desired, and the disk is then retained in adjusted position 20 by means of a spring 31, the free end of which is recurved to engage with any selected one of a series of notches 32 cut in another portion of the disk's periphery.

Adjacent the other face of ratchet wheel 25 (the outer face as shown) is a second disk 33 of somewhat similar character, in that its diameter, for a portion of its circumference, is equal to or greater than the maximum diameter of said ratchet wheel 30 so as to shroud the teeth thereon. Normally this disk 33 is positioned as shown in Figs. 1 and 2, so as not to interfere at all with the operation of dog 24. However, by means of a rod 34, a lever 35 on said disk 33 35 is connected with a lever arm 36 on rock shaft 6, so that whenever the latter is operated through the medium of throw-off lever 9 said disk will be moved into the position indicated in dotted outline in Fig. 40 1, whereby the teeth on ratchet wheel 25 are shröded throughout the complete range of movement of the dog. The continued movement of the latter is accordingly rendered ineffective to feed more ink, and operation 45 of the fountain ceases until the press is restored to normal operating condition by reverse movement of said lever 9.

The mode of operation of my improved inking mechanism has, it is believed, been 50 sufficiently set forth in connection with the foregoing description of the construction and operation of its several component parts. It will be seen that, by means of the spring 31, the automatic fountain can be 55 set to feed the ink at any desired rate when the press is normally operating, while, through the medium of connecting rod 34, whenever the throw-off lever 9 is operated to prevent the form from contacting with 60 a sheet on the platen, the feeding of ink will be simultaneously entirely stopped. In this way the accumulation of an abnormal quantity of ink on the form rollers and disk, and consequent smearing of the form and 65 work, is entirely avoided.

Other modes of applying the principle of my invention may be employed instead of the one explained, change being made as regards the mechanism herein disclosed, provided the means stated by any of the following claims or the equivalent of such stated means be employed. 70

I therefore particularly point out and distinctly claim as my invention:—

1. In a platen printing press provided with a throw-off adapted to shift the bed of said press without interrupting operation of the platen, the combination with an ink fountain mounted above the inking disk of said press, said fountain including 80 an ink-feeding roller, a ratchet wheel connected therewith, an oscillatory arm, and a pawl on said arm adapted to progressively rotate said wheel; of connections between said arm and the roller frame of 85 said press adapted to operate the former in unison with the latter; a disk adapted to shroud said wheel and thereby limit the operative effect of said pawl; and means adapted to position said disk. 90

2. In a platen printing press provided with a throw-off adapted to shift the bed of said press without interrupting operation of the platen, the combination with an ink fountain mounted above the inking 95 disk of said press, said fountain including an ink-feeding roller, a ratchet wheel connected therewith, an oscillatory arm, and a pawl on said arm adapted to progressively rotate said wheel; of connections between 100 said arm and the roller frame of said press adapted to operate the former in unison with the latter; a disk adapted to shroud said wheel and thereby limit the operative effect of said pawl; and manually operable means adapted to retain said disk in desired position. 105

3. In a platen printing press provided with a throw-off adapted to shift the bed of said press without interrupting operation of the platen, the combination with an ink fountain mounted above the inking disk of said press, said fountain including 110 an ink-feeding roller, a ratchet wheel connected therewith, an oscillatory arm, and a pawl on said arm adapted to progressively rotate said wheel; of connections between 115 said arm and the roller frame of said press adapted to operate the former in unison with the latter; a disk adapted to shroud said wheel and thereby limit the operative effect of said pawl; and a resilient member adapted to engage said disk and retain same in desired position. 120

4. In a platen printing press provided 125 with a throw-off adapted to shift the bed of said press without interrupting operation of the platen, the combination with an ink fountain mounted above the inking disk of said press, said fountain including 130

an ink-feeding roller, a ratchet wheel connected therewith, an oscillatory arm, and a pawl on said arm adapted to progressively rotate said wheel; of connections between 5 said arm and the roller frame of said press adapted to operate the former in unison with the latter; a disk adapted to shroud said wheel and thereby limit the operative effect of said pawl; and means connected 10 with said throw-off adapted to position said disk.

5. In a platen printing press provided with a throw-off, the combination with an ink fountain mounted above the inking disk 15 of said press, said fountain including an ink-feeding roller, a ratchet wheel connected therewith, an oscillatory arm, and a pawl on said arm adapted to progressively rotate said wheel; of connections between 20 said arm and the roller frame of said press adapted to operate the former in unison with the latter; a disk adapted to shroud said wheel and thereby limit the operative effect of said pawl; manually oper- 25 able means adapted to retain said disk in desired position; a second disk adapted to

shroud said wheel and similarly limit the operative effect of said pawl; and means connected with said throw-off adapted to position said second disk. 30

6. In a platen printing press provided with a throw-off, the combination with an ink fountain mounted above the inking disk of said press, said fountain including an ink-feeding roller, a ratchet wheel connected therewith, an oscillatory arm, and a pawl on said arm adapted to progressively rotate said wheel; of connections between 35 said arm and the roller frame of said press adapted to operate the former in unison with the latter; a disk adapted to shroud said wheel and thereby limit the operative effect of said pawl; a resilient member adapted to engage said disk and adapted to retain same in desired position; a second 40 disk adapted to shroud said wheel and similarly limit the operative effect of said pawl; and means connected with said throw-off adapted to position said second disk. 45

Signed by me, this 21st day of April, 50
1919.

RALPH S. TYLER.
